Attorney

UNITED STATES PATENT OFFICE

CHARLES W. PARKER, OF OMAHA, NEBRASKA

AIR-DIRECTING AND IGNITION-ELECTRODE SUPPORT FOR OIL-BURNERS

Application filed November 12, 1928. Serial No. 318,891.

My invention relates to oil or liquid-fuel burners of the nozzle type, employing high-tension electrical ignition means, and having air-directing devices for effecting a gyratory motion of air past the nozzle from which the liquid fuel is sprayed. It is the object of my invention to provide for burners of this kind a combined air-directing device and insulating support for the ignition-electrodes, whereby the desired flow of air past the nozzle may be effected without being interfered with by the electrode-supports and insulators. A further object of my invention is to provide means for retaining the air-directing electrode-support in adjusted relations to the fuel-nozzle. A further object is to provide improved means for connecting to the electrodes the high-tension conductors of the ignition-circuit.

In the accompanying drawings Fig. 1 is a longitudinal section of a liquid-fuel burner provided with means embodying my invention, the section being on the plane of the line 1—1 of Fig. 3, Fig. 2 is a horizontal section of the air-tube, showing in plan the parts inclosed thereby, and Fig. 3 is an inner end view of the burner.

Liquid-fuel burners of the type to which my invention is applicable are characterized by the use of a nozzle 5 which is carried at the end of the pipe 6 through which the fuel is supplied under pressure, the nozzle having at the end thereof a minute aperture 7 through which the fuel emerges in a fine spray, to become mixed with air, ignited and burned. The fuel-pipe 6 is arranged centrally of much larger pipe or tube 8 through which the air is supplied for combustion of the fuel, the air usually being under forced draft, impelled by a suitable fan or blower. The tube 8 is extended through the wall of the furnace to the combustion-chamber thereof, said tube terminating substantially at the inner side of the wall, and the fuel-pipe being so arranged that the end of the nozzle 5 is approximately flush with the inner end of the air-tube. The high-tension electrical igniting means for the burner includes a pair of elec-

trodes 9 having terminal portions 10 of which the ends are suitably positioned and spaced apart for the passage of the ignition-spark at a point adjacent to the stream of fuel sprayed from the nozzle-aperture 7. 55

In burners of this type it is highly desirable, and practically essential, to provide means for producing a whirling or gyratory motion of the air about the fuel-nozzle, whereby to insure uniform distribution of the air about the emerging spray of fuel, and to thus produce a clean, uniform and properly directed flame within the combustion-chamber of the furnace. The desired gyratory motion of the air is readily effected by means of suitable helicoidal vanes or blades held fixedly in the air-tube adjacent to the nozzle, but great difficulty has been encountered heretofore in effecting the desired control of the air-currents, by reason of the following: The electrodes, and the wires or conductors by which the same are connected with the source of electrical energy, pass through the air-tube alongside the fuel-pipe, it being necessary that the electrodes be adequately supported to maintain their terminals 10 in proper relation to each other and to the fuel-spray, and that the electrodes be suitably insulated to prevent leakage of the high-tension current. The 75

insulators for the electrodes, and the supporting means for such insulators, are necessarily located in proximity to the nozzle, and in burners as heretofore constructed it has been found that the presence of the insulators and the supporting means therefor has interfered seriously with the desired gyratory motion of the air produced by the helicoidal air-directing blades, causing the air to emerge about the fuel-nozzle asymmetrically thereto, and resulting in an imperfectly formed and directed flame, and inefficient combustion of the fuel. 85

The foregoing difficulties and objections are entirely overcome by the means provided by my invention, said means consisting primarily of an air-directing device formed wholly of high-grade insulating material such as glazed porcelain, said air-directing device being constructed and ar- 95 100

ranged to form the support for the ignition-electrodes, and thereby entirely replacing the usual insulators and supports for the electrodes. In the illustrated structure, the 5 insulating, air-directing member comprises a tubular hub 11 adapted to fit loosely upon the fuel-pipe 6, and having formed integrally therewith a plurality of helicoidal blades 12, preferably arranged symmetrically about the hub and of such radial extent as to pass freely through the air-tube 8. Two of the blades, preferably those above the horizontal axial plane of the device, have bosses or cylindrical lugs 13 formed 10 integrally therewith, said lugs extending parallel with the hub-axis and being located intermediate the hub and the outer ends of the blades. The electrodes 9 pass longitudinally through said lugs 13, being placed 15 therein when the insulating material is molded, and each electrode having, inclosed by the insulating material, a flattened or non-cylindrical portion 14, serving to anchor the electrode in the material and prevent 20 displacement thereof either by longitudinal movement or rotation.

The insulating, air-directing member is held in adjusted relations upon the fuel-pipe 6 by means of a pair of metal collars 30 15 and 16, secured to said pipe at the ends of the hub 11 by means of small set-screws 17. A lug 18 is formed integrally with the collar 15 at the side thereof adjoining the inner end of the hub 11, said lug being 35 adapted to extend into a similarly formed notch or recess in the end of the hub, and thereby serving to prevent movement of the hub about the pipe.

The outer ends of the electrodes 9 are 40 preferably threaded to receive the coupling-members 19 by which the wires 20 are connected therewith. Said coupling-members 19 are cup-shaped, being threaded at one end to fit upon the threaded ends of the 45 electrodes, and at the other end having a small opening through which the stranded, flexible wires 20 may be passed after the insulating covering 21 has been stripped 50 from a short portion thereof. After being passed through said opening, the end portions of the stranded wire are spread into the bottom of the threaded portion of the coupling, so that said spread portions of 55 the wire will be clamped and firmly held when the end of the electrode is screwed 60 against the same. A mechanically and electrically efficient connection of the wires with the electrodes is thus effected without soldering, welding, or the use of means 65 which might project laterally toward the fuel-pipe 6 or the air-tube 8, with consequent liability of leakage or short-circuiting of the ignition-circuit.

It will be apparent that the described 70 structure and arrangement of parts enables

the electrodes to be effectively insulated and supported in the desired relation to the fuel-nozzle, without interfering, or with a minimum of interference, with the gyratory air-currents caused by the helicoidal blades of 75 the air-directing device; and that the devices may be inexpensively produced, and easily and quickly assembled and adjusted to a proper operative relation.

Now, having described my invention, what 80 I claim and desire to secure by Letters Patent is:

1. In a liquid fuel burner of the class described, the combination with a fuel-nozzle, and a fuel-pipe extending to and supporting said nozzle; of an air-directing member and electrode-support formed integrally of insulating material and comprising an annular central portion fitting 85 about said fuel-pipe, and a plurality of helicoidal blades extending outwardly from said annular central portion; electrodes extending substantially parallel with the fuel-pipe through the intermediate portions of some of said blades and supported solely 90 thereby; and means for securing said air-directing member and electrodes in adjusted relations to the nozzle, said means comprising collars secured upon the fuel-pipe, one of said collars having parts interengaged 95 with the annular central portion of said member to prevent turning thereof about the fuel-pipe.

2. In a liquid fuel burner of the class described, the combination with a fuel-nozzle, and a fuel-pipe extending to and supporting said nozzle, of an air-directing member formed integrally of insulating material and comprising an annular central portion fitting 100 about said fuel-pipe, and a plurality of blades extending outwardly from said annular central portion; electrodes affixed to said blades intermediate the ends thereof and extending therefrom substantially parallel with the fuel-pipe; and means for securing the air-directing member in adjusted relations to the nozzle, said means including a collar secured to the fuel-pipe and having parts interengaged with the annular central portion of said air-directing 105 member to prevent turning thereof about the fuel-pipe.

CHARLES W. PARKER.
